UNITED STATES PATENT OFFICE.

WILLIAM WILSON GOURLAY AND JAMES W. GOURLAY, OF SOUTH VINELAND, NEW JERSEY.

ELEVATING-ROD-ACTUATING DEVICE.

1,117,661.

Specification of Letters Patent.

Patented Nov. 17, 1914.

Application filed October 11, 1912. Serial No. 725,257.

To all whom it may concern:

Be it known that we, WILLIAM W. GOURLAY and JAMES W. GOURLAY, citizens of the United States, residing at South Vineland, 5 in the county of Cumberland and State of New Jersey, have invented new and useful Improvements in Elevating-Rod-Actuating Devices, of which the following is a specification.

10 This invention relates to attachments for linotype machines and more particularly to the actuating mechanism for the assembling elevator or assembler blocks of the type used in the Mergenthaler machine.

15 One of the principal objects of the invention is to provide a simple and efficient attachment whereby the assembler block may be conveniently elevated without the necessity of the operator removing his hand from 20 the key-board.

25 Further objects of this invention will appear as the following specific description is read in connection with the accompanying drawing which forms a part of this application, and in which the figure is a diagrammatic view showing the device arranged alongside of the ordinary key-board of a Mergenthaler machine and connected to the usual assembler block.

30 In the preferred construction of the device A represents the ordinary assembler block which is operated through a rotating shaft B connected to the block by a link C and elevator rod D, the rod B being turned 35 in the usual manner by the hand lever E. The attachment comprises a standard 1 which is bolted to the floor adjacent the linotype machine and has pivoted in its upper end a lever 2 connected to the foot pedal 3 0 by means of a link 4, the link being pivoted both to the pedal and to the lever 2. The end of the pedal opposite its connection with the link is pivoted to a floor plate 5 secured to the floor. The lever 2 has the end opposite 5 to the one connected to the link 4 provided with a longitudinal slot 6 which receives a lateral pin 7 formed on the lower end of the

elevator rod D. The rod is guided in any suitable manner as by a guide 8 secured to the machine or to any other suitable support. 50 The upper end of the link 4 is preferably provided with a plurality of apertures 9 whereby the connection of the lever 2 with the link 4 may be adjusted when desired thereby permitting the floor plate 5 to be attached to a surface whose plane is higher or lower than the surface to which the standard 1 is secured and yet obtain the proper inclination of the foot pedal. A spring 10 extends from one end of the lever 2 to the base 60 so that when the foot pedal is released the assembler block A will lead to normal position and the foot pedal elevated for a second operation.

What is claimed is:—

65 An elevating rod actuating device including a base, a standard rising from and formed integral with said base, a lever pivotally connected at its medial portion to the extreme upper inner face of said standard 70 and having an elongated slot formed longitudinally thereof in one of its ends, an elevating rod, a pin projecting laterally from the extreme lower end of said rod, said pin passing through the slot of said lever, and 75 yieldable means disposed in a vertical plane with the standard and connected at one end with said pin and the slotted end of the lever and at its other end with the base for restoring the elevating rod to normal position, 80 a manually operated member, and means connected at one end with the latter mentioned member and adjustably connected at its other end with the opposite end of said lever for connecting the latter with said 85 manually operated member.

In testimony whereof we affix our signatures in presence of two witnesses.

WILLIAM WILSON GOURLAY.
JAMES W. GOURLAY.
